UNITED STATES PATENT OFFICE.

ALBERT W. KAPFER, OF BUFFALO, NEW YORK.

CLASP FOR SCARFS, NECKTIES, AND THE LIKE.

Application filed August 30, 1923. Serial No. 660,168.

To all whom it may concern:

Be it known that I, ALBERT W. KAPFER, a citizen of the United States, residing at Buffalo, in the county of Erie and State of New York, have invented new and useful Improvements in Clasps for Scarfs, Neckties, and the like, of which the following is a specification.

This invention relates to a clasp which is 10 more particularly intended for use in connection with scarfs or neckties to secure the same about the neck of the wearer and to simulate the four-in-hand tie without tying the usual knot.

15 One of the objects is to provide a novel clasp of this character which will reliably retain the end portions of the tie neatly together and be positively secured against displacement relatively thereto.

20 Another object of the invention is to provide an ornamental tie clasp which can be readily applied to and removed from the tie and which always insures a perfect appearing knot with the tie-ends of uniform length.

25 In the accompanying drawings: Figure 1 is a perspective view of a collar and tie showing the improved clasp in connection therewith. Figure 2 is a rear view of the clasp. Figure 3 is a transverse vertical section on line 3—3, Fig. 2. Figure 4 is a horizontal section on line 4—4, Fig. 2. Figure 5 is a perspective view of the clasp-retaining member. Figure 6 is a similar view of the clasp-band. Figure 7 is a perspective view 30 of a modified form of clasp-retaining member.

Similar characters of reference indicate corresponding parts throughout the several views.

40 10 indicates a collar and 11 a tie associated therewith, the improved clasp being shown in position on the tie to simulate the well-known four-in-hand knot.

In the embodiment of the invention shown 45 in Figs. 1—6, inclusive, the same consists of two parts, including a band 12 adapted to encircle those portions of the tie adjacent to the collar and produce the effect of a four-in-hand knot, and a detachable locking or 50 retaining member 13 mounted on said band and adapted to engage and grip the tie to prevent slippage of the band relatively thereto. The band 12, which may be constructed of metal or other appropriate material, is preferably frusto-conical in shape,

being of larger diameter at its upper end than at its lower end. The rear side of said band is open, as shown at 14, and the opposing ends thereof terminate in suitable guides or tongues 15 which extend from the top to 60 the bottom thereof.

The locking or retaining member 13 is movably mounted on the band 12 to move lengthwise thereof and occupies the space 14 at the rear side of the band 12, the same 65 being provided in its opposite longitudinal edges with grooves 16 which engage the corresponding tongues 15 of said band. This retaining member may be constructed of the same material as the band and it is preferably wedge-shaped, increasing in thickness from its lower to its upper end, as shown in Figs. 3 and 5. By making the locking member in the form of a wedge, those portions of the tie embraced by the 70 band 12 are compressed and drawn together sufficiently to retain the clasp frictionally in its proper position. Furthermore, the employment of this wedge-shaped retaining member renders the clasp applicable to ties 75 of different materials; if made of a comparatively thin material the retaining member will obviously be forced further downward relative to the band, than would be necessary if the tie was made of a heavier 80 material, in order to reliably hold the clasp 85 in place. To further prevent accidental displacement of the clasp on the tie, the inner face of the retaining member may be provided with spurs or teeth 17 which bite into 90 the tie and hold the clasp against slipping or turning out of its set or operative position.

The rear face of the retaining member is preferably flush with the contiguous side of 95 the band 12 and conforms to the contour thereof, whereby there are no protruding parts to interfere with the convenient application and removal of the clasp.

In applying this clasp to the necktie, 100 those portions of the latter adjacent to the collar are brought together so as to overlap each other, after which the clasp-band 12 is slipped over such end portion and the retaining member 13 is fitted in the open back 105 of said band with its major portion projecting above the top of the latter. After setting the band in the position desired at the front of the collar, the retaining member is pushed downwardly on the band so 110

as to securely hold the clasp in such position.

The modified form of the retaining member shown in Fig. 7, instead of being wedge-shaped, consists of a bar or plate 18 slidably mounted on the band and provided on its inner face with a yieldable tongue or clamping jaw 19 which co-operates with the opposing wall of the band to securely hold the clasp properly in position on the tie. This yieldable jaw may be provided with a spur or tooth 20 which may be punched from the body thereof or otherwise formed thereon. This type of retaining member is particularly intended for use in connection with light-weight ties, while the wedge-like retaining member, previously described, is better adapted for use with ties of heavier material.

20 Aside from performing the function of simulating a four-in-hand knot, this device also acts as an ornament and may be provided in its front side with a jewel, emblem or the like, that shown in the drawings, by way of example, having initials 21 thereon.

This improved clasp is easily and quickly applied to and removed from the tie without wrinkling and without injury thereto, 30 it produces a perfect and neat-appearing knot which is always maintained in its proper position and in which the tie-lengths are always uniform. Furthermore, it is simple and compact in construction and can be manufactured at a moderate cost.

I claim as my invention:

1. A necktie-clasp of the character de-

scribed, comprising a tie-encircling band open at one side, a retaining member fitted in the open side of said band and conforming to the curvature thereof, and teeth on the inner face of said retaining member for engaging the portions of the tie extending through the band to prevent slippage of the latter relative to the tie.

2. A necktie-clasp of the character described, comprising a frusto-conical tie-encircling band open at one side, the opposing edges formed by said open side constituting guides, a retaining member fitted in the open side of said band and engaging said guides, said member being of substantially the same length as said band, and devices formed on the inner side of said retaining member and engaging the portions of the tie extending through said band for preventing displacement of the clasp relative to the tie.

3. A necktie-clasp of the character described, comprising a tie-encircling band open at one side, and means slidably fitted in the open side of said band and having a yielding clamping jaw extending into the interior of the band for engaging the portions of the tie extending through said band.

4. A necktie-clasp of the character described, comprising a split tie-encircling band, a retaining member detachably mounted between the opposing edges of said band, and a yieldable clamping jaw carried by said retaining member and extending into the interior of the band.

ALBERT W. KAPFER.
